Victor J. Evans

ATTORNEY

UNITED STATES PATENT OFFICE.

HOWARD McDOWELL, OF LEWISTOWN, ILLINOIS.

GAME APPARATUS.

Application filed October 31, 1927. Serial No. 230,016.

This invention relates to game apparatus, an object being to provide an apparatus of this type which may be placed upon a regular or pocket billiard table and used by one or more players.

Another object of the invention is the provision of a game apparatus in which chance as well as skill will be an important factor, so that a poor or inexperienced player, and 10 a good or expert player will be more evenly matched.

With the above and other objects in view, the invention further includes the following novel features and details of construction, 15 to be hereinafter more fully described, illustrated in the accompanying drawing and pointed out in the appended claims.

In the drawing:

Figure 1 is a plan view showing the apparatus in position upon a billiard table.

Figure 2 is a sectional view on the line 2—2 of Figure 1.

Figures 3 and 4 are sections taken respectively on the lines 3—3 and 4—4 of Figure 1.

Referring to the drawings in detail where in like characters of reference denote corresponding parts, the reference character 15 indicates a portion of a regular or pocket 30 billiard table, the rails of which are indicated at 16.

The improved game apparatus is adapted to be placed upon the table at the end opposite "scratch" and comprises a base 17. 35 This base is supported upon spaced tapered rails 18 which are secured transversely of its bottom, so that the upper face of the base is inclined downwardly from the adjacent end of the table toward the center.

Secured to and extending longitudinally 40 of the base adjacent its lower edge is an upwardly disposed strip 18'. This strip forms the inner ends of pockets 19, the side walls of which are formed of strips 20.

The strips 20 extend toward the upper edge 45 of the base 17 and terminate short of this edge. The outermost strips, that is, the strips which form the outer walls of the end pockets, are spaced from the opposite ends 50 of the base. A rail 21 extends along the upper edge and each end of the base and

this rail together with the adjacent strips 20 form the side walls of passages 22 whose inner ends communicate with the space between the ends of the strips 20 and the rail 55 21. The bottoms of the pockets 22 are inclined as shown at 23, so that the entrance ends 24 of these pockets have their edges so formed as to permit of the ready entrance of a rolling ball. The base and pockets are 60 covered and lined with a suitable lining 25 of felt, so that the balls will readily roll over the base and into the pockets.

Each of the pockets is numbered as indicated in Figure 1 of the drawings, and the 65 players roll the ball from "scratch" along the top of the table through the passages 22, and when momentum of the ball is checked it will gravitate into one of the pockets. The rail 21 assists in checking and 70 guiding the ball. The pockets may be consecutively numbered as shown, or they may have the numbers arranged in any other manner. The player having the highest 75 score in a predetermined number of rolls or plays will win the game.

The invention is susceptible of various changes in its form, proportions and minor details of construction and the right is herein reserved to make such changes as properly fall within the scope of the appended 80 claims.

Having described the invention what is claimed is:

1. The combination with a billiard table, 85 of a game apparatus adapted to be placed at one end of the table and comprising an inclined base, a duplicating rail extending along each end and longitudinally of the uppermost edge of the base, pockets positioned upon the base with their open ends opposed to and spaced from the longitudinally extending rail and passages provided between the end rails and the adjacent sides of pockets and communicating with the 90 space between the pockets and the longitudinal rail.

2. A game apparatus comprising a flat inclined base, a strip extending longitudinally adjacent one edge of the base and terminating short of each end, partition strips 100 extending transversely of the base from the

longitudinal strip and terminating short of the other longitudinal edge of the base and defining a longitudinal passage with transverse pockets opening into the passage, a
5 rail extending along the upper and side edges of the base and cooperating with the partition strips of the pockets to provide

side passages which communicate with the longitudinal passage, inclined bottoms for the side passages, and indicia for each of 10 the pockets.

In testimony whereof I affix my signature.

HOWARD McDOWELL.
